William W. Watts

UNITED STATES PATENT OFFICE.

WILLIAM WEBSTER WATTS, OF BIRMINGHAM, ENGLAND.

SHOE-HOLDING DEVICE.

SPECIFICATION forming part of Letters Patent No. 417,454, dated December 17, 1889.

Application filed April 5, 1889. Serial No. 306,118. (No model.) Patented in England April 27, 1888, No. 6,231.

To all whom it may concern:

Be it known that I, WILLIAM WEBSTER WATTS, manufacturer, of Birmingham, England, a citizen of the United Kingdom of Great Britain and Ireland, have invented 5 certain new and useful Apparatus for Holding Boots or Shoes while being Cleaned and for Treeing and Stretching Same, (for which I have obtained provisional protection in England, dated April 27, 1888, No. 10 6,231;) and I do hereby declare that the following is a full, clear, and exact description of the invention, which will enable others skilled in the art to which it appertains to 15 make and use the same.

This invention has reference to an improved apparatus for holding boots or shoes while being cleaned and polished, and also for treeing and stretching same, and is an improvement 20 on Letters Patent of the United States of America granted to me for a device for holding boots or shoes, dated November 29, 1887, and numbered 374,023, the present invention being designed to further facilitate 25 the operation of cleaning, polishing, or dressing, while at the same time it can be used for treeing and stretching boots or shoes when distorted or otherwise misshapen by the effect of wear, damp, or ill-usage.

The nature, construction, and operation of 30 my invention will be readily understood on reference to the accompanying drawings.

Figure 1 represents the apparatus *per se*; Fig. 2, the apparatus mounted on a suitable 35 bench or stool, and showing a boot in position for cleaning, polishing, treeing, or stretching; and Fig. 3 is a detail view, hereinafter referred to.

Similar letters of reference indicate like 40 parts in all the figures where they occur.

A is a base-plate provided with a web for the purpose of being screwed down to a table or shelf, as may be found convenient. The vertical arm b is provided with a curved slot 45 c, in which moves a stud or pin c', projecting from the lever-handle d, which latter works on the pivot e. To this handle is pivoted a tongue f, the free end of which carries a saddle g, capable of accommodating itself to the 50 inside of different-sized boots or shoes.

h is a pawl gearing in the ratchet h', so that when the lever-handle is drawn forward to effect the necessary pressure of the tongue toward the toe of the boot or shoe the pawl prevents its return until released. Instead 55 of the pawl and ratchet as thus described, the handle-pin c' may be formed so as to constitute a thumb screw and nut, whereby the handle can be held in any required position 60 in the slot.

A platform i rises from the base-plate on which the boot or shoe is placed. This platform is slightly concave on its upper surface, so as to present clearly-defined longitudinal edges, whereby additional grip is afforded 65 and lateral movement of the boot or shoe prevented while being operated upon. It is also provided at the heel with sharp claws p, which engage with the heel of the boot or shoe, as hereinafter described. In order to 70 keep the tongue f slightly raised from the platform, (when not in use,) a spring l is fixed to the vertical arm and bears against the tongue, so that the latter is always in a position of readiness to receive a boot or shoe; or 75 a spiral spring m may be used instead of that just described.

For portability the vertical arm b may be made detachable from the base-plate by means of a dovetailed joint, as shown in Fig. 3. 80

The action of the invention is briefly as follows: Having inserted the tongue f in the boot or shoe, the latter is placed on the platform i, with the front of the heel against the point p of the platform. The handle d is then 85 drawn forward, which causes the tongue to travel toward the toe of the boot or shoe, carrying same forward and causing the heel to press tightly against the platform-points p. When the pressure necessary to grip firmly 90 the boot or shoe is thus effected, the pawl engages in the ratchet and prevents the return of the handle and tongue.

The apparatus as thus constructed may be mounted on a suitable stool or bench, as shown 95 in Fig. 2; or it may be attached to a table or shelf, as found convenient.

Having thus described the nature of my 100 said invention, I would have it understood that I do not confine myself to the precise de-

tails herein specified and illustrated, as the same may be varied without departing from the principle of my invention; but

What I claim is—

- 5 1. The device for cleaning, polishing, treeing, stretching, or holding boots or shoes, the apparatus consisting of a base-plate A, vertical arm b, and tongue f, in combination with the platform i, and heel-abutment point or points p, and mechanism for forcibly separating the parts f and p, whereby a boot or shoe is held firmly by the administration of pressure inside toward the toe end and contact or pressure at the heel end, substantially 10 in the manner described.
- 15 2. In a device for the purpose described, the combination, with the base-plate having point p and vertical arm provided with curved slot, of the lever d, having a stud working in

said slot, the platform, the tongue pivoted at one end to the said lever, and the saddle g, carried by the free end of the tongue, substantially as shown and described.

3. In a device for the purpose described, the combination, with the base-plate having point p and provided with a vertical arm having curved slot, of the lever d, having a stud working in said slot, the platform, the tongue pivoted at one end to the lever, the saddle g on the free end of the tongue, and the spring connecting the lever with the tongue, substantially as shown and described.

Dated this 30th day of January, 1889.

WILLIAM WEBSTER WATTS.
